SAND TRAP CLEANOUT

Frank E. Saari, Chicago, and Grant V. W. Roth,
Evanston, Ill., assignors to Monarch Equipment
Co., Chicago, Ill., a corporation of Illinois

Application November 18, 1949, Serial No. 128,152

2 Claims. (Cl. 291—11)

1

The invention relates to a sander, of the compressed air type, for railway track use, and has for one purpose to provide a sander with an improved clean-out.

Another purpose is to provide a sander with a clean-out of maximum structural simplicity.

Another purpose is to provide a clean-out which, when it is operated, prevents leakage or supply of sand from the sand source.

Another purpose is to provide an improved clean-out method for railway sanding.

Another purpose is to provide a method for converting existing sanding devices to the employment of the improved clean-out principle.

Other purposes will appear from time to time in the course of the specification and claims.

The invention is illustrated more or less diagrammatically in the accompanying drawings wherein:

Figure 1 is a vertical axial section;

Figure 2 is a plan view, on a reduced scale, of a modification of the structure shown in Figure 1;

Figure 3 is a side elevation of the structure of Figure 2, with parts in axial section;

Figure 4 is a side elevation of the fitting shown in Figure 5;

Figure 5 is a section on the line 5—5 of Figure 4; and

Figure 6 is a partial vertical axial section illustrating a method of converting a simplified type of existing equipment to practice the present invention.

Like parts are indicated by like symbols throughout the specification and drawings.

It will be understood that the sander may be applied in any suitable manner to existing track sanding equipment, the sand supply and the delivering piping being not herein shown in detail.

Referring to the drawings, 1 generally indicates any suitable sand reservoir container or bucket in which a supply of sand 2 is present, or through which such supply flows. Figure 1 illustrates a sander assembly which is shown as including a single casting 3 connected by the externally threaded duct 4 to the sand container 1. The sand initially flows into a pocket or trap 5, having a relatively restricted neck 6 between a lower lip or dam 7 and an upper constriction 8. Thus a supply of sand 9 may at all times be kept in the pocket or trap 5, being supplied through the duct 4 from the main sand body 2. When sand is not being supplied, the body of sand 9 will terminate in an inclined face between the portions 7 and 8. 10 is a portion of

the sanding structure shown in the form of a tube. Whereas we show in the drawings a downwardly inclined tube or tubular chamber, it will be understood that this is a matter of illustration, not of restriction.

A sand delivery pipe 11 may be threaded into or secured to the portion 10 in any satisfactory manner, and may constitute means for moving sand toward the point of ultimate use.

10 20 is an air supply duct which delivers air to an inlet passage 21 shown as formed in any suitable lug or projection 22 of the general unit. 23 is any suitable restriction valve shown as having a portion 24 threaded into any suitable aperture 25 in the projection 22. It is shown as having an external head 27. 28 is a lock nut abutting against the surface 29 of the casting, whereby the valve 23 may be locked at any desired setting in relation to the inner air passage 20 30 for controlling the air flow to, and thus through, the ducts 31 and 32. The passage 30 has one branch 31 shown as axially aligned with and extending to the interior of the casting portion 10. The duct 30 also delivers air to a duct 25 32 through which air may pass into the trap 5. 33 is any suitable threaded plug to provide access to the duct 32.

It will be understood that when air is supplied through the air supply duct 20 some air is admitted into the sand in the trap 9, and the rest of the air is delivered axially along the interior tubular chamber 10a of the passage portion 10. Thus sand is pneumatically agitated in and expelled from the trap 5, the expelled sand being carried along the tubular chamber or passage 10a to and through the sand delivery pipe or conduit 11. This takes place only when suitable valve means are employed; for example, when the operator of a locomotive wishes to deliver sand to the rails. The means for controlling the air flow to the trap do not, of themselves, form part of the present invention, and are not herein shown. It will be understood that compressed air is normally used, that being the practice of the railroads.

It is desirable, before a sanding operation, to clean out the sand supplying pipe system from the trap to the point of use, to eliminate any foreign material that may be present, such as moisture, ice, etc. It is also desirable to clean any sand that may be left in the pipe after the sanding. This is done with a larger volume of compressed air, which is supplied through the larger diameter pipe 41 and the duct or passage 50 55 40. It is important, when performing the clean-

out function, that additional sand should not be wasted through the pipe 11. In order to effect the double purpose of an adequate clean-out and a restraint of waste sand a principle, novel in the clean-out field, is employed. Air pressure is maintained against the surface 6a of the sand, while, at the same time, delivering a conveying current of air along the sand delivering pipe. Referring, for example, to Figure 1, 40 illustrates an air inlet, which is shown as perpendicular to the axis of the chamber 10a, and, preferably, as intersecting the axis of the chamber 10a. Air is supplied through any suitable air supply pipe 41, shown as threaded as at 42, and screwed into the internally threaded projection 43. It will be understood that when air has been delivered through the pipe 20 to deliver sand, and after the termination of air delivery through the pipe 20, air is then delivered through the pipe 41 and through the relatively restricted orifice 40. The result is to maintain pressure against the sand face 6a, while delivering adequate clean-out air along the pipe 11.

In Figure 1 there is shown a unitary structure including the sand trap and the clean-out. In Figures 2 and 3 the clean-out is employed or applied as a separate element.

Referring to Figures 2 and 3, a sand trap body, or a casting 3a, not employing a clean-out, may be employed, which is identical with the casting 3 of Figure 1, except that the chamber portion 10 is somewhat shorter, and the clean-out inlet duct 40 is omitted. Instead, there is provided a connecting duct or pipe 11a, which may be of any suitable length, and there is employed a separate clean-out fitting, generally indicated as 50. It is in the form of a T, having opposite parallel ends 51 and 52, with a restricted clean-out inlet 53 located perpendicularly to the axis of the chamber 10a, the pipe 11a, and the T-positions 51 and 52. 11b is any suitable pipe extending to or toward the point of delivery of the sand. The system of supplying the conveying and the clean-out air is the same in the form of Figures 2 and 3 as in Figure 1. The separate clean-out fitting or unit is illustrated in Figures 4 and 5. While we do not wish to be limited to any specific means for securing the clean-out unit, we find it convenient to thread the branches 51 and 52 internally, as shown in Figures 3 and 4, and to provide an internally threaded lateral projection 55 to receive the pipe 41 which delivers the clean-out air.

In Figure 6 we illustrate a type of sand trap which includes a different form of clean-out, but which may be converted to employ the principle of the present invention. The trap or sanding body 60 will be understood to have within it a body of sand 61 which, when sand is not being delivered, has a front face 62. In the fitting as originally supplied a clean-out duct 63 is employed in communication with the threaded interior 64 of the projection 65 which receives the air pipe 66. Any suitable sand delivery pipe 67 is threaded into or otherwise secured to the end 65 of the unit 60. When the unit, as originally formed, is used, with the clean-out passage 63 delivering air angularly toward the passage 67, some degree of vacuum is set up between the passage 63 and the sand face 62. The result is that during the clean-out blast of air through the pipe 66, sand is entrained from the sand face 62, and is wasted along the passage 67. We find that when we close the passage 63 and drill or form a perpendicular passage 63a, shown in dot-

ted line in Figure 6, we obtain a satisfactory clean-out delivery of air, while avoiding any entrapment or entrainment of air from the sand face 62.

5 The use and operation of the invention are as follows:

In the form of Figure 1 we illustrate a unitary sand trap and clean-out structure to which compressed air must be delivered by the passage 20 for sanding purposes. The dam 7 serves as a limit for the sand, when the clean-out operation is not going on, and the sand face 6a inclines upwardly and to the right therefrom, referring to the position of the parts as shown in Figure 1. 10 After the sanding operation, clean-out air is delivered through the pipe 41 and the restricted inlet duct 40. The fact that the axis of delivery of the air is at right angles to the axis of the chamber 10a, the pipe 11 permits or causes adequate delivery of clean-out air along the pipe 11, but, at the same time, maintains air under pressure against the sand face 6a, and causes no pick-up or wastage of sand from the sand face.

15 The forms of Figures 2 and 3 operate in the same way, it being a matter of convenience whether or not a separate fitting 50 is employed, with its clean-out air inlet or duct 53. An advantage of the employment of a separate unit 50, such as is shown in Figures 2 to 5, is that it may be located at a variety of distances from the sand face 6. Also, it may be applied to convert existing sand trap structures to the employment of our invention. Under some circumstances, it may be an advantage to do as shown in Figure 6, in converting old equipment. That is to say, any suitable means may be employed for blocking any inclined passage, such as the passage 63, while a substitute perpendicular passage 63a is drilled.

20 We find that the angle or axis of delivery of the clean-out air, in relation to the line of flow of the sand, is critical. That is to say, in a structure identical with that shown in Figures 1, or 2 and 3, if the axis of the restricted passage 43 or 53 is inclined either toward or against the direction of flow of the sand, the result is sand wastage and undesired carrying of sand by the clean-out blast of air. Even a slight inclination of the passage 40 may destroy the advantages of the structure described and shown herein.

25 It will be realized that, whereas we have described and illustrated a practical and operative device, nevertheless many changes may be made in the size, shape, number and disposition of parts without departing from the spirit of our invention. We therefore wish our description and drawings to be taken as in a broad sense illustrative or diagrammatic, rather than as limiting us to our precise showing.

30 For example, whereas we have illustrated units with a single clean-out air inlet, it will be understood that it is within the scope of our invention to employ a plurality of such inlets.

We claim:

35 1. In combination with a sand delivery conduit, a clean-out assembly including a normally open connection between a supply of sand and the said sand delivery conduit, said connection comprising a tubular chamber having, intermediate its ends, a compressed air supply duct with its delivery axis substantially perpendicular to the longitudinal axis of said tubular chamber, said air supply duct having a restricted delivery opening of a cross-sectional area substantially less than that of the said tubular chamber.

2. The method of converting a clean-out assembly for a sand delivery passage which includes rendering inoperative any already existing clean-out air supply passage and providing a substitute clean-out air supply passage with its axis of compressed air delivery substantially perpendicular to the axis of the said sand delivery passage, said air supply passage having a restricted delivery opening of a cross-sectional area substantially less than that of the sand delivery passage. 10
